A. H. Rauch,

Bottle Cleaner.

No 11,000.

Patented June 6, 1851.

UNITED STATES PATENT OFFICE.

A. H. RAUCH, OF BETHLEHEM, PENNSYLVANIA.

MACHINE FOR WASHING BOTTLES.

Specification of Letters Patent No. 11,000, dated June 6, 1854.

To all whom it may concern:

Be it known that I, AMBROSE H. RAUCH, of Bethlehem, in the county of Northampton and State of Pennsylvania, have invented a new and useful Improvement in Machines for Washing Bottles; and I do hereby declare that the following is a full, clear, and exact description of the same, reference being had to the accompanying 10 drawings, forming part of this specification.

Figure 1, is a front elevation, and partial section of the machine, as it appears when prepared for, or is in, operation. Fig. 2, is a vertical transverse section of the same, as 15 it appears when ready to receive the bottles, the treadles being depressed, the fork or hollow cone for causing the bottle to revolve being elevated, and the flexible or expanding and folding brush and frame, being 20 shown folded ready to be inserted into the bottle. Fig. 3, is a detached view of the water pipe, and the expanding or folding frame or brush, it being shown unfolded, and as it appears when in the bottle, and in 25 use.

Similar letters of reference in each of the several figures indicate corresponding parts.

This invention relates to certain new and useful improvements whereby bottles of all 30 sizes and descriptions can be washed perfectly clean, on their outer and inner surfaces at the same time, with great facility and despatch.

The nature of my invention consists, in 35 a rectangular shaped folding brush, which has three of its sides made of solid strips, and set with brushes or bristles, which serve to cleanse the bottom, shoulder and sides of the bottle, at one operation, while its 40 other side is made hollow, and serves as a canal for supplying a constant stream of clear water to the interior of the bottle, to facilitate the cleansing operation; and the whole being united together by hinge joints, 45 in such a manner that, when the brush is folded, the cross-piece which carries the brush for cleansing the bottom of the bottle will assume a position in line, and parallel with the hollow stem, while the pieces carrying the side and shoulder brushes, assume 50 a vertical position in line with each other, and lie parallelly and snugly alongside the stem and cross strip which carries the bottom brush. By thus constructing folding 55 brushes, great compactness with durability

is secured, which is an important desideratum in such a device; for it is necessary to have it small enough to enter with facility, the neck of different sized bottles; and, at the same time, durable and capable of bearing the strain and resistance brought against it, (as the bottle revolves), after the bristle holes have been drilled in it on one side, and the wire course cut in it on the other side. The want of compactness has long 60 been the difficulty attending the expanding brush, as is the case in the expanding brush, illustrated in *Brevets l'Invention*, vol. 72, plate 23.

When this brush is folded, the three framing pieces lie on top of each other. This way of arranging and connecting the parts, renders the brush so bulky when folded, that it cannot, with facility, be inserted into the bottle, if it is made strong enough to withstand the strain and wear to which it is subjected, when the bottles are kept running by machinery.

My invention consists, 2d, in the employment of the revolving adjustable hollow cone, or its equivalent, which is so arranged and operated, that it takes hold on the bottom of the bottle, (which is inverted, and has its mouth resting in a socket), and causes it to revolve rapidly, when the machinery is in operation, and brings its inner and outer surface in contact with the inside and outside cleansing brushes.

My invention consists, 3d, in the employment of the stationary inside and outside brushes, arranged in the manner herein described, in combination with the revolving cone, and inside and outside branch pipes of the elevated reservoir, which supply constant streams of clean water to the inside 90 and outside of the bottle the whole rendering the operation of washing bottles by machinery very convenient and effectual, as will be hereinafter shown.

My invention also consists in arranging a 95 spring between the stem and the side brush—said spring serving to expand the brush as shown as it gets into the body of the bottle.

My invention consists, 5th, in a novel self adjusting arrangement for accomplishing three different objects simultaneous with one another: 1st, for folding the expanding frame and retaining it thus ready for entering the mouth of the bottle; 2d, for ele- 100 105 110

vating or adjusting the revolving cone, so that it may be out of the way when the bot-
5 ble is being placed over the expanding brush; and 3d, for shutting off the supply of water while putting another bottle, to be washed, over the expanding brush.

To enable others skilled in the art to make and use my invention, I will proceed to describe its construction and operation.

10 A, represents a frame to, and in which the mechanism for performing the operations beforementioned, is attached and arranged. This frame may be made after the plan shown, or any other more appropriate; it having a partition or horizontal platform, 15 B, for the bottles to rest upon while being washed; and there being a suitable trough or receptacle, C, to catch and hold the dirty water until it runs off through the pipes ap-
20 propriated for the purpose.

D, is the hollow tube or stem of the inside brush; it passes up vertically through the bottle carrier, a, and then passes into the bottle in the manner shown in Fig. 1. The carrier, a, which fits in the stand, serving to keep the pipe, D, in proper position, and also to receive the mouth of the bottle, as shown in Fig. 1. The pipe, D, is open at its top, so as to discharge the water into the bottle; it is also coupled, by a link nut, b, to another short vertical pipe, D', which communicates with the main pipe, F, as seen in Fig. 1. The object in dividing the vertical pipe into two sections, D, D', is, 30 that D, may be elevated or lowered, so as to raise or lower the expanding brush, and thereby adapt it to different heights of bottles; the link nut, b, serving to adjust the same as may be requisite.

40 G, is a cock, in the short pipe, D', for letting on, and shutting off the supply of water from the main pipe, F; this cock and its operation will be described hereafter—it being connected to the arrangement for 45 keeping folded the inside brush, and is operated simultaneously with the folding of the same.

H, is the expanding frame, which carries the material for cleaning out the inside of 50 the bottle. It may be composed of metal strips, united together by loose hinge joints, d, e, and then hinged to the stem, D, by joints, e, f, in such a manner, that they can fold together, as shown in Fig. 2, so as to be capable of entering bottles having very small mouths, or necks. This frame, after 55 passing into the bottle, is caused to expand, as shown in Figs. 1, and 3, by means of the spring, g.

60 I, are the bristles which are secured in the side, bottom, and shoulder strips of the frame, H, and serve to wash the entire inner surface of the bottle.

J, is a branch pipe from that, D'; it 65 serves to supply water to wash the outside of

the bottle; this pipe passes up through the stand, B, in the manner shown in Fig. 1, and 2.

K, is the brush for rubbing the dirt from off the outside of the bottle; it is of such shape, and placed in such position that it will wash the entire side and neck of the bottle clean. Its position is shown clearly in Fig. 1, where it is represented suspended on the standard, L, and operating upon a 75 bottle.

In Fig. 1, the machine is represented as performing the operation; water being shown coming from the reservoir, and passing up through the pipe, D, D', and branch, J, into the bottle, and against its outside, and then descending and passing out through the mouth of the bottle, and down its outside, from which it continues its course, and falls into the receptacles, C, M, N, and passes off through the pipes, O, P, Q. 80

85 It should be mentioned, that while the water is being injected into, and up, against the outside of the bottle, that the bottle has a rapid revolving motion communicated to it through the cone, P, which fits around its bottom; and, as the motion is communicated to the said cone by means of the pulley and bands, at the top of the machine, it is caused to revolve, and consequently, the bottle with it; the cone may be employed for this purpose, or a fork having three spring teeth, or tines, may be used instead thereof.

90 The machine may be driven by hand, through the crank shaft, h, or by steam or otherwise through the driving shaft, i; the bevel gearing, j, k, giving the required speed.

95 To elevate the cone, I attach a vertical jointed rod, S, to the treadle, and connect it with the shaft of the cone, in the manner shown in Fig. 2. And, to operate the cock, G, and thereby shut off the water, I attach an arm, T, to the square end of the cock, and attach the other end of said arm by a set screw, to the vertical joint rod, S, in the manner shown in Figs. 1, and 2. The set screw plays freely in an oblong slot, formed in the arm, T. As said arm and vertical rod, S, adjust themselves to the downward, 100 or upward, movement of the treadle, one of said movements opening the cock, and the other closing it. And to retain the brush, or expanding frame folded, and ready to pass into the bottle, simultaneous with the operation of raising the cone and shutting the cock, I make the rod, S, of tapering 105 shape, for a portion of its length, as seen in Fig. 2, at V, so that when the treadle is raised, this wedge, V, will be caused to compress the spiral spring, W, and cause it to act on the pendulous folder, X, whose weighted end is forced rigidly against the expanding frame, H, and made to retain it 110 folded in the manner shown in Fig. 2, till 115

120 125 130

the bottles are placed over the tube, D; when the treadles are caused to descend, and the cone with them. The spring, W, expands; the weighted lever falls to its original position; the cock, G, opens; and the water flows into the bottle—as soon as this is done, the machine, if not already in motion, is again started, and the bottle and cone made to revolve rapidly against the 10 brushes, and stripped of its impurities.

A bottle having been washed, the machine continues running. The treadle is depressed by the foot, at the same time the washed bottle is grasped by the hand, and raised 15 with the cone,—the expanding frame, as it makes its exit from the bottle falls folded into the embrace of the spring, or pendulous folder, and is retained in that state by the same, until the spring is released, which 20 should not be before another bottle has been presented, with the bottom in the cone, and neck down into the carrier. The operator has the dirty bottle in his right hand, and after depressing the treadle, takes the clean 25 one away with his left hand, and places the dirty one in its place; and, when it is properly set, releases his hold, and withdraws his weight from the treadles, and the washing commences.

30 This machine, as represented in the drawing, has "two run of bottles," or two stands for bottles. A machine may, however, have a larger number—say six—in which case, the bottles will have a longer time to be in 35 motion, each running the length of time it takes to change the other five. It is, however, necessary to have the expanding frame and outside brushes suited to the size of the bottles; as various sizes can be washed in the 40 same machine, but not by the same size of brush.

The machine does not, of necessity, stop to have a new set of bottles put into it, while the clean ones are removed. It being 45 so constructed with an adjustable dog on the cone shaft, which uncouples the cone from the motion, while up, and couples it to the motion, while down.

I do not claim a folding brush for washing bottles, independent of its peculiar construction, as such brushes have been used before; but,

What I do claim, is—

1. A rectangular shaped folding brush, 55 which has three of its sides made of solid strips, and set with bristles, which serve to

cleanse the shoulder, periphery, and bottom of the bottle, at the same operation, while its other side is made hollow, and serves as a canal for introducing a constant 60 stream of clean water to the interior of the bottle, to facilitate the cleansing operation; and the whole united together by loose joints, c, d, e, f, in such a manner, that when the brush is folded, the cross-piece which 65 carries the brush for cleansing the bottom of the bottle, will assume a position in line, and parallel with the hollow stem, while the pieces carrying the side and shoulder brushes, assume a vertical position in line 70 with each other, and lie parallelly and snugly alongside the stem and bottom brush, substantially as, and for the purpose herein set forth.

2. I do not claim washing bottles in an 75 inverted position; but what I do claim, is:—the employment of the revolving cone, or its equivalent—which is so arranged and operated, that it takes hold on the bottle, which is inverted, and has its mouth resting in a socket, a, and causes it to revolve rapidly, when the machine is in operation, and brings its inner and outer surface in contact with the inside and outside cleansing brushes, substantially as herein de- 80 scribed.

3. I claim the employment of the stationary inside and outside cleansing brushes, in combination with the revolving cone; and inside and outside branch pipes of the elevated reservoir—the whole being constructed, arranged, and operating in the manner, and for the purpose herein described.

4. I also claim the self-adjusting arrangement for accomplishing the three following 95 objects:—1st, folding the expanding frame, and retaining it thus, ready for entering the mouth of the bottle; 2d, for elevating the revolving cone, so that it may be out of the way, when the bottle is being placed over 100 the brush; and 3d, for shutting off the supply of water, while putting another bottle to be washed, over the expanding brush.

5. I claim arranging a spring between the supply stem and the side strip of the brush 105 frame, H, for the purpose of expanding the brush, as soon as it enters the body of the bottle, as herein fully set forth.

A. H. RAUCH.
